CLAIM

The ornamental design for a family prayer altar, as
shown and described.

DESCRIPTION

FIG. 1 is a right front perspective view of a family
prayer altar showing my new design, the cross shown
fragmented for ease of illustration; and

FIG. 2 is a front perspective view thereof.

The left side of the family prayer altar of FIG. 1 is a
mirror image of the right side as shown therein.

The back of the altar is substantially plain, without
ornamentation, except for the cross attached thereto.
